UNITED STATES PATENT OFFICE.

HARRY D. BUSH, OF NEW YORK, N. Y.

BUILDING CONSTRUCTION.

SPECIFICATION forming part of Letters Patent No. 438,678, dated October 21, 1890.

Application filed April 4, 1890. Serial No. 346,585. (No model.)

To all whom it may concern:

Be it known that I, HARRY D. BUSH, of New York, in the county and State of New York, have invented a new and useful Improvement 5 in Building Construction, of which the following is a specification.

The object of my invention is to improve the manner of constructing partitions from boards or slabs such as those described in

10 Patent No. 386,102, dated July 10, 1888.

I will proceed to describe the form in which I prefer to embody my invention, and more particularly point out its essential features in the claims.

15 Figure 1 represents a partly-constructed partition - wall, with the floor and ceiling beams in side view. Fig. 2 represents a vertical section of the same. Fig. 3 represents a horizontal section of the same. Fig. 4 represents details enlarged. Figs. 5, 6, 7, 8, and 9 represent certain modifications.

a is the ceiling-beam, to which the studs are attached at the top. *b b' b''* are the floor-beams, to which the studs are connected at their bottoms.

25 *c c' c'' c'''* are the studs. The most simple form of these studs is shown in Figs. 1 to 4, inclusive, consisting of a single piece of iron containing a web *d*, from one extremity of which projects at right angles the flange *e*, and from the other extremity of which projects in the opposite direction at right angles the flange *f*. Instead of being constructed of a single piece of iron, the studs, however, may be constructed as shown in Figs. 5, 6, and 9, in which the web *d'* is made separate from the flanges, and the flanges are constructed by fastening the angle-irons *e'* and *f'* to opposite ends of the web.

30 Another form of the studs is shown in Figs. 7 and 8. Here the web, instead of being composed of a continuous piece of iron, is made up of the separate cross-bars *d''*, extending from the angle-iron *e'* to the angle-iron *f'* and secured in the position shown; also, of the cross-bars *d'''*, secured as shown. The bars *d''* and *d'''* may be arranged as shown in Fig. 8, so that the same bolt or rivet may answer to secure two of the bars to each of the 45 angle-irons.

The studs are secured to the floor and ceiling beams, respectively, by the angle-irons *g*

g', as shown in Fig. 1, having one flange bolted to the floor or ceiling beam, as the case may be, and the other flange bolted to the web of the stud.

In general the fire-proof boards will be applied as shown in Figs. 1, 2, and 3. *h h' h''* represent the boards of one partition. *h'''* represents the boards of the partition at right angles thereto.

It will be observed that every two adjacent studs are placed so that their flanges on the same side of the partition are directed toward each other, as shown in Fig. 3.

65 It is obvious that after the studs are set up and secured in place, as shown in Fig. 3, the boards *h'* can be placed in position against the opposing flanges of the studs *c c'* from the side of the partition shown by arrow *x*, 70 and that the boards *h''* can be placed in position from the side of the partition shown by arrow *y*, or that they can be diagonally passed through the space between the studs and drawn back squarely into position if it is important or convenient to have all the boards delivered on the same side of the partition. The boards *h'''* of the partition at right angles 75 may be placed in a similar manner, the same stud *c''* being used to secure the ends of the boards *h''* and *h'''* by halving or otherwise interlocking the ends of the boards together, as in Fig. 1.

The boards can be held in place by hooked bolts *i* or by large-headed wire nails *i'*, passed 85 through the board and then clinched down over the flange *f*, as shown in Fig. 4, or by countersunk bolts *i''* passing through the flange of the studs and through the board. Where either of the first two methods of fastening the boards is employed, the boards should be made a trifle thicker than the cross-width of the stud, as shown in Fig. 3, so that the plaster or hard finish which is applied to the boards may be made to completely cover the ends of the bolts or nails, as the case may be, as well as the flanges of the iron studs. Where countersunk bolts, as *i''*, are employed, their nuts are let into the plaster-boards.

90 At a suitable height on the studs small brackets *j j'* may be riveted, suitable for supporting a picture-molding, if desired.

100 In case a partition of more than a single

thickness of boards is desired the construction shown in Fig. 9 may be employed. Here the boards $h' h^2$ are supplemented by the boards $h^4 h^5$, separated, so as to make an air-space between, by the filled pieces $k k' k^2 k^3$. It is evident that such thick fire-proof walls as these last described would be very useful for large temporary buildings for great exhibitions, &c. The iron frame-work could be put up complete, with boards of suitable length rapidly fitted between the studs and fastened with large bolts, whose heads and nuts may be left visible or not, as wished. The structure could, moreover, be readily taken down without destroying the material.

I claim—

1. A wall containing, in combination, a series of **Z**-formed studs having their flanges turned alternately in opposite directions and a series of panels secured to said studs alternately from opposite sides of said wall, substantially as described.

2. In combination, two walls forming an angle with one another and each composed of a series of **Z**-formed studs having their flanges turned alternately in opposite directions and a series of panels applied to said studs from opposite sides of the walls, the adjacent ends of the panels at the union between the two walls interlocking, substantially as described.

3. A wall containing a series of **Z**-formed studs having their flanges turned alternately in opposite directions, in combination with a series of panels applied alternately on opposite sides of said wall, each of said panels consisting of an inner and an outer thickness separated by a filler, substantially as described.

HARRY D. BUSH.
